(57) **CLAIM**

The ornamental design for a crib, as shown and described.

DESCRIPTION

FIG. 1 is a perspective view showing our new design for a crib.

FIG. 2 is a front side plan view thereof, the back side being a mirror image, but forms no part of the claimed design.

FIG. 3 is a cross-section plan view along lines 3—3 of FIG. 6.

FIG. 4 is a top plan view thereof.

FIG. 5 is a cross-section plan view along lines 5—5 of FIG. 6.

FIG. 6 is a side plan view of a portion of FIG. 2, the opposite side of the portion being a mirror image.

FIG. 7 is a right side plan view thereof, the left side being a mirror image; and,

FIG. 8 is a bottom plan view thereof.

The broken lines adjacent the shaded areas represent the boundaries of the claimed design, while the other broken lines representing the outline of the crib are for illustrative purposes only, and form no part of the claimed design. The broken lines shown along the cross-section in FIG. 3 is for illustrative purposes only, forms no part of the claimed design, and represents the interior portions of the material forming the design.
